UNITED STATES PATENT OFFICE.

STANLEY C. WISE, OF CANONSBURG, PENNSYLVANIA, ASSIGNOR TO CONTINENTAL CAN COMPANY, INC., OF SYRACUSE, NEW YORK, A CORPORATION OF NEW YORK.

TIN-PLATE-PILING APPARATUS.

Application filed May 26, 1924. Serial No. 715,960.

To all whom it may concern:

Be it known that I, STANLEY C. WISE, a citizen of the United States, residing at Canonsburg, in the county of Washington,

5 State of Pennsylvania, have invented certain new and useful Improvements in Tin-Plate-Piling Apparatus, of which the following is a description, reference being had to the accompanying drawing, and to the figures 10 of reference marked thereon.

The invention relates to new and useful improvements in an apparatus for piling plates of sheet metal, and more particularly to an apparatus which is capable of receiving 15 the sheets of tin as they come from the cleaning machine used in connection with the coating of sheets and the stacking of the same in an even pile on the skid.

Black sheets or sheets of steel after being 20 properly prepared are coated with tin, and thus tin plate is formed. After the sheets are coated, they must be cleaned in order to remove the oil or grease therefrom which is used in the coating process. This is usually 25 done by means of a cleaning machine such as shown in the patent granted to J. C. Taliaferro and C. M. Reynard, September 16, 1902, No. 709,184. It has been customary 30 in connection with this machine to allow the sheets as they come one after another from the cleaning machine to pile up promiscuously in the receiving receptacle from which they are taken by hand to a bench where they are stacked in even piles.

35 The present invention has for its object to receive the sheets as they come from this cleaning machine one after the other, and to pile these sheets in even stacks on skids which may be bodily lifted so that the piled 40 sheets may be taken to the proper place for final inspection and crating.

In the drawings—

Figure 1 is a perspective view showing the apparatus embodying my improvements;

45 Fig. 2 is a sectional view through a portion of the apparatus and showing diagrammatically the sheets passing from the inclined table to the stack.

Fig. 3 is a sectional view on the line 3—3 50 of Fig. 1.

In carrying out the invention, I have provided an apparatus which includes a sup-

porting framework on which is mounted a table adapted to be moved from one inclined position to another, and said framework is 55 positioned at the delivery end of the cleaning machine so that the sheets as they come from the cleaning machine, will drop on to this inclined table. The inclination of the table is in a direction at right angles to the direction of travel of the sheet as it comes from the cleaning machine, and is of sufficient extent as to cause the sheets to slide off from the inclined table. The sheet which falls on the inclined table will slide off from the said table before the next sheet reaches the 60 table. So it is that the sheets will be taken, one after another, and directed by the inclined table into a stacking device. At one side of the frame carrying the inclined table is a skid on which are mounted side plates and an end plate for forming a stack of sheets. There is also attached to the table frame a plate for directing the sheets as they are stacked and thus evening up the other 65 end of the sheets. The sheets received one at a time by this stacking device form an even pile, and after the proper number of sheets have been piled, then the table is tilted 70 so as to throw the sheets to the other side of the frame where they are received by an independent stacking device. While one pile or stack is being formed, the other may be conveyed to a suitable place and another skid provided and the stacking devices assembled thereon. Thus it is that by changing the skids and the stacking devices, the 75 sheets may be stacked automatically in piles and without in any way stopping the cleaning machine.

90 The cleaning machine is so well known to those skilled in the art that I have not thought it necessary to illustrate it more than the delivery end thereof, which is shown at C in Figure 1 of the drawings. 95 As the sheets pass out from the end of the cleaning machine, they have heretofore been received promiscuously on the table and taken by hand and stacked on skids or conveyors. According to my improved apparatus, however, I have provided a supporting frame 1 consisting of suitable frame members, which is adapted to be placed at the delivery end of the cleaning machine.

Mounted on said frame 1 is a receiving table 2. Said receiving table 2 is preferably made up of a series of boards 3, 3 connected by cross pieces 4, 4 (see Fig. 4). Located 5 midway the sides of this table is a pivot rod 6 which is secured to the table by suitable brackets 7. This pivot rod extends beyond the side edges of the table. Mounted on the frame 1 is a bracket 8 which is secured to 10 the upper edge of the frame. This bracket is deflected upwardly at the center portion thereof where there is provided a journal for the pivot rod 6. It will be understood, of course, that there is a bracket 8 at each 15 side of the frame, and the purpose of deflecting the bracket upwardly centrally thereof is to raise the pivot rod so that the table can be set at an inclination sufficient for the purpose of sliding the sheets. The 20 table is preferably covered by metal members 9. These metal members 9 are provided with downwardly and inwardly turned side edges 10 which are adapted to extend about the edge of the table (see Fig. 2). 25 The metal forming this covering for the table is turned upwardly so as to provide a wall 11 which may be suitably reinforced, if desired. There is also a member 9^a similarly constructed which likewise engages 30 the side edge of the table, and these two members are telescoped one within the other, as clearly shown in Figure 1 of the drawings. The members, therefore, may be readily slid one on the other so as to regulate 35 the distance between the upstanding walls 11 and 11^a of the two members. These are adjusted according to the size of the sheets being cleaned, so as to leave ample space for the receiving of the sheets one after another, 40 but permitting the free sliding of the sheets off from the table. The table is set at a proper inclination for receiving and sliding the sheets by means of a lever 12 which is pivoted at 13 to the table and is 45 adapted to engage a locking lug 14 carried by the frame 1. Said lever has notches 15 adapted to engage the lug, and a handle 16 by which the lever may be manipulated. When the table is set as shown in Figure 1, 50 the sheets received thereon will slide off from the table at the right hand side thereof. If the lever should be swung so as to tilt the table in the opposite direction, then the sheets will slide off from the left hand 55 side of the table.

Associated with this table at each side thereof is a receiving skid and stacking members. When the table is set as in Figure 1, the skid 17 is operative to receive the 60 sheets as they slide from the table. In order to stack the sheets one on the other evenly and thus form an even pile, I have provided an end member 18 and two side members 19 and 20, arranged at opposite 65 sides of the skid. I have also provided an

end member 21 which is pivoted at 22 to the frame 1 and is supported thereby. The end member 21 is in the form of a right angle in cross section, with the short leg of the right angle hinged to the frame. The long 70 leg is vertical and located over the inner side of the skid 17, so that said vertical portion of the end member 21 will determine and form that side of the piled sheets. The member 20 is made of metal and may be reinforced in any suitable way. Said reinforced sheet is secured to angle brackets 23 and 24. These brackets are adapted to be mounted on removable lugs 25 which may be detachably hinged to the skid, and which 75 project outwardly from the side edge thereof. The bracket is adjustably secured to the supporting lug by means of a bolt 26 which passes through a slot 27 in the bracket. The bracket 24 is similarly secured to a supporting lug, and this is likewise true of the brackets for supporting the side member 19. The end member 18 is connected to similar brackets 23^a which are secured to lugs 25^a similar in construction to the lugs 25, by means of bolts 26^a. The purpose is to provide a supporting means for these side and end members so that they may be adjusted and held rigidly in vertical position. A suitable pad or the like may be attached 95 to the end member 18 so that the sheets as they slide off from the table, will strike endwise against the pad and will drop on to the skid. The plates 9 and 9^a are properly set so as to direct the sheet between the side 100 members 19 and 20.

In Figure 2 of the drawings, I have shown a sheet S as received by the table 2 and sliding off the table. Said sheet passes over the upper edge of the end plate 21 and in 105 between the side plates 19 and 20 as indicated in dotted lines at S'. It will strike against the end plate 18 as indicated by the dotted line S², and then will fall on to the stack which is indicated at S³. After the stack has been piled a suitable height, then the operator reverses the inclination of the table 2 and the sheets will slide therefrom on to the skid 17^a at the 110 other side of the frame 1, and the sheets will be piled between the side plates 19^a and 20^a carried by the skid 17^a. The end plate 18^a will direct the sheets as they are piled. The end member 21 as stated above, is pivoted to the frame, and said end member is 115 provided with an angle bracket 28. A brace member 29 is pivoted to this angle bracket 28 and is provided with a notch or recess 30 which is adapted to engage the vertical wall of an angle plate 31 secured to and located centrally of the base portion of the frame 1. This brace rod holds the wall 21 in fixed position during the piling of the sheets. The brace rod, however, may be disconnected from the angle bar so that 120 125 130

the same can readily swing back out of the way. The side members 19^a and 20^a and the end member 18^a are adjustably supported in the same manner as the end and side members associated with the skid 17. The side members are provided with angularly arranged portions 32, to permit the adjustment of the side members and to aid in the directing of the sheets between the same. These angularly arranged members also stiffen the side members. The end member 18 is likewise provided with these angularly arranged portions 32. The upper edges of these side and end plates may be rolled, if desired, to strengthen the same. The edges of these side plates and the means for supporting said plates may be varied greatly. The essential feature consists in the providing of adjustable stacking plates in conjunction with the supporting skid, which plates may be removed and associated with another skid for forming another stack, while the stacking plates on the skid are removed by the conveying of the skid itself with the stacked sheets to the desired place.

Of course, it is obvious that minor changes in the arrangement of the parts may be made without departing from the spirit of the invention as set forth in the appended claims.

Having thus described the invention, what I claim as new and desire to secure by Letters Patent, is—

35. 1. A sheet piling apparatus for a tin plate cleaning machine comprising a receiving table on to which the sheets are discharged in succession from the cleaning machine, a piling skid at each side of the table, means for inclining the table so that the sheets received thereby will slide either to one side or the other on to a piling skid, and means associated with each piling skid for evenly piling the sheets thereon.
45. 2. A sheet piling apparatus for a tin plate cleaning machine comprising a receiving table on to which the sheets are discharged in succession from the cleaning machine, a piling skid at each side of the table, means for inclining the table so that the sheets received thereby will slide either to one side or the other on to a piling skid, and means associated with each piling skid for evenly piling the sheets thereon, said piling means associated with the skids being removable and adjustable so that said piling means is adapted to be used with different size sheets and may be removed from the skid and applied to another piling skid.
55. 3. A sheet piling apparatus for a tin plate cleaning machine comprising a supporting frame, a receiving table pivotally mounted in said frame, means for adjustably holding said table in an inclined position so as to discharge the sheets either at one side or the

other of said frame, a piling skid at each side of the frame adapted to receive the sheets from the receiving table, and means associated with each skid for forming an even pile of sheets thereon.

4. A sheet piling apparatus for a tin plate cleaning machine comprising an inclined receiving table for receiving the sheets from the cleaning machine and discharging the same one at a time therefrom, a piling skid associated with the receiving table, and means associated with the piling skid for evenly piling the sheets thereon, said last-named means being adjustable and removable so that sheets of different sizes may be piled and so that when a pile has been formed upon one skid, the skid may be replaced by another and the piling means attached thereto.

5. A sheet piling apparatus for a tin plate cleaning machine comprising an inclined receiving table located at the discharge end of the cleaning machine and inclining in a direction to one side of the cleaning machine whereby sheets of tin received from the cleaning machine will be discharged one at a time sidewise from the receiving table, and means for receiving and piling the sheets discharged from the receiving table.

6. A sheet piling apparatus for a tin plate cleaning machine comprising an inclined receiving table located at the discharge end of the cleaning machine and inclining in a direction to one side of the cleaning machine whereby sheets of tin received from the cleaning machine will be discharged one at a time sidewise from the receiving table, means for receiving and piling the sheets discharged from the receiving table, said receiving table having a metal cover including adjustable sections and guiding ledges so that the piling apparatus may be adapted for sheets of different sizes.

7. A sheet piling apparatus for a tin plate cleaning machine comprising a supporting frame, a receiving table mounted thereon and inclining toward one side of the frame, said table having metal sections with ledges which are adjustable one upon the other so as to be set for different width sheets, a skid associated with the frame and spaced therefrom so that the sheets sliding from the receiving table will pile one upon the other on the skid, said plates being removably and adjustably carried by the skid for evening the pile of sheets, and an end plate also removable and adjustably carried by the skid for evening the end of the pile.

8. A sheet piling apparatus for a tin plate cleaning machine comprising a supporting frame, a receiving table mounted thereon and inclining toward one side of the frame, said table having metal sections with ledges which are adjustable one upon the other so as to be set for different width sheets,

a skid associated with the frame and spaced therefrom so that the sheets sliding from the receiving table will pile one upon the other on the skid, said plates being removably and adjustably carried by the skid for evening the pile of sheets, and an end plate also removable and adjustably carried by

the skid for evening the end of the pile, an end plate hinged to the frame for evening the opposite end of the pile, and a brace rod for rigidly holding said last-named end plate in said position for piling. ¹⁰

In testimony whereof, I affix my signature.
STANLEY C. WISE.
